LEAF AND TRASH GATHERER

Fred V. Belluomini, P.O. Box 644, Jackson, Calif.

Filed June 29, 1959, Ser. No. 823,614

3 Claims. (Cl. 15—257.4)

The present invention is directed to and it is a major object to provide a novel, manually portable device for domestic or light commercial use to gather leaves and trash and to then carry the accumulated debris to a discharge or dumping point; the device being readily hand-supported and manipulated.

Another important object of the invention is to provide a leaf and trash gatherer which includes a handle-supported, initially open top receptacle normally disposed in a vertical carrying position but movable under control of the handle to and from a horizontal loading position; the top of the receptacle being provided with a hinged cover, and there being means to automatically open and close the cover when the receptacle is moved, respectively, to and from said horizontal loading position. Thus, whenever the receptacle is in horizontal loading position, the cover is open so that debris may be swept into said receptacle, and when in vertical carrying position, the cover is closed so that the debris in said receptacle cannot accidentally escape or be blown out by the wind.

An additional object of the invention is to provide a leaf and trash gatherer wherein the handle remains at all times in a position upstanding from the receptacle; there being a novel catch unit which automatically but manually releasably locks the receptacle to the upstanding handle upon movement of said receptacle to horizontal loading position. The handle is formed—at its upper end—with a grip, and the aforesaid catch unit includes a release trigger adjacent said grip for ready finger engagement and actuation.

It is also an object of the invention to provide a leaf and trash gatherer which is designed for ease and economy of manufacture and convenience of use.

A still further object of the invention is to provide a practical, reliable, and durable leaf and trash gatherer, and one which is exceedingly effective for the purpose for which it is designed.

These objects are accomplished by means of such structure and relative arrangement of parts as will fully appear by a perusal of the following specification and claims.

In the drawings:

Fig. 1 is a perspective view of the leaf and trash gatherer in its vertical carrying position.

Fig. 2 is an enlarged rear elevation of the leaf and trash gatherer in the position of Fig. 1; the upper portion of the upstanding handle and related parts being broken away.

Fig. 3 is a sectional elevation taken on line 3—3 of Fig. 2.

Fig. 4 is a similar view, but shows the leaf and trash gatherer in its horizontal loading position.

Referring now more particularly to the drawings and to the characters of reference marked thereon, and by reference to the positions of the parts when the device is in its vertical carrying position, such device comprises an initially open top receptacle indicated generally at 1.

2

The receptacle 1 is of lightweight sheet metal construction and includes sides 2 of trapezium shape, a front 3, a back 4 of lesser height than the front 3, and a bottom 5. The top opening of the receptacle 1 thus inclines 5 rearwardly and downwardly from the upper edge of the front 3, as shown for example in Fig. 1. A girth-band 6 is fixed to and surrounds the receptacle 1 in substantially the plane of the upper edge portion of the back 4; such girth-band being above the gravitational dead 10 center of said receptacle 1.

A grate-like cover 7 is disposed on the receptacle 1 in normally closing relation to the open top thereof; such cover being hinged, as at 8, at its lower edge to the portion of the girth-band 6 at the upper edge of the 15 back 4.

A fork-leg handle, indicated generally at 9, straddles the upper portion of the receptacle 1 and upstands thereabove, such handle 9 including an upstanding tubular post 10 formed at its upper end with a relatively short 20 rearwardly projecting hand grip 11. Adjacent but short of its lower end, the post 10 is fitted with laterally outwardly extending, downwardly inclined legs 12, and such legs include vertical lower end portions 13 which depend in spaced relation outwardly of the sides 2. At their 25 lower ends the leg portions 13 are pivoted, as at 14, to the girth-band 6 substantially centrally between the front 3 and back 4.

A horizontal, cover actuating rod 15 extends transversely between and is secured at the ends to the upper 30 ends of the leg portions 13; i.e. closely adjacent the point of bend in the legs 12. As so mounted, the cover actuating rod 15 normally spans—in spaced relation—above the cover 7 intermediate the upper and lower edges thereof.

A pair of guide or retention rods 16 are mounted in connection with the cover 7 and extend from adjacent the lower edge thereof to a point ahead of the cover actuating rod 15; such guide or retention rods 16 converging upwardly and being mounted in stand-off relation to the cover 7, with said cover actuating rod 15 disposed under said guide or retention rods 16; i.e. between the latter and said cover 7. The cover actuating rod 15 thus normally occupies a position beneath the guide or retention rods 16 adjacent the upper ends 45 of the latter.

Adjacent but short of its lower end, the upstanding tubular handle post 10 is fitted exteriorly thereof, and on the back side with a vertically elongated weight 17 which includes a vertical inwardly projecting web 18 which passes through a longitudinal slot 19 in post 10; such web 18 being grooved on opposite sides, as at 20, for the reception in guiding relation of the adjacent portions of the post 10 on opposite sides of said slot 19. The weight 17 is thus mounted for guided up and 55 down motion.

A pull rod 21 is disposed within the post 10 and such pull rod is connected, at its lower end, to the web 18 while the upper end of said pull rod is connected to the shank 22 of a trigger 23 slidably mounted on the back 60 side of said post directly below the hand grip 11. A finger of the hand which engages the grip 11 can conveniently engage and pull upwardly on the trigger 23 whereby to impart corresponding movement to the pull rod 21 and weight 17; the latter being one element of a catch unit, the details of which will hereinafter appear.

An upstanding tubular handle 24 is disposed adjacent but outwardly of the back 4 of receptacle 1 and centrally of its sides; such handle including a forwardly extending 65 upper attachment bar 25 and a corresponding lower attachment bar 26. At its inner end, the attachment bar 25 is secured to the girth-band 6, while at its inner end

the lower attachment bar 26 is secured to the bottom 5 as shown.

At substantially the point of bend between the handle 24 and its upper attachment bar 25, such handle is formed with an outwardly opening notch 27. The lower end of the weight 17 is formed as a cam-faced catch 28, which catch lies in the same vertical longitudinal plane as the notch 27. Upon swinging of the receptacle 1 from its vertical carrying position, as in Fig. 1, to its horizontal loading position, as in Fig. 4—and at which time the post 10 remains in an upstanding position, the cam-faced catch 28 snap-engages, under the influence of the weight 17, in the notch 27. This effectively locks the fork-leg handle 9 in an upstanding position on the receptacle 1 when the latter is in its horizontal loading position.

Additionally, and to laterally stabilize the fork-leg handle 9 when the receptacle 1 is in said horizontal loading position, the portion of the post 10 below the catch 28 is cut away, as at 29, to define a cradle including side ears 30 which straddle said attachment bar 25. Further, a dog 31 is inturned from the lower end of post 10 and engages in a notch 32 in the upper attachment bar 25 when said fork-leg handle 9 is in its latched or locked position.

To release the receptacle 1 for return to its vertical carrying position from the horizontal loading position, the user lifts the entire device by the grip 11 and then pulls upwardly on the trigger 23 which withdraws the catch 28 from the notch 27 whereupon said receptacle 1 gravitationally swings back to said vertical carrying position.

As hereinbefore described, the grate-like cover 7 is normally closed; i.e. when the receptacle 1 is in its vertical carrying position. However, when such receptacle 1 is manipulated by the fork-leg handle 9 between said vertical carrying position and horizontal loading position, and which is accomplished by swinging of the receptacle forwardly and downwardly preferably while in ground engagement, the cover 7 is automatically opened. This occurs by reason of the cover actuating rod 15 sliding under and along the guide or retention rods 16 in the direction of the upper edge of the back 4. As a consequence, and when the fork-leg handle 9 is in a position upstanding from the then horizontally disposed receptacle 1, said cover actuating rod 15 has swung the cover 7 to a substantially vertical open position as shown in Fig. 4. Conversely, when the receptacle 1 is caused to swing between its horizontal loading position and its vertical carrying position, the rod 15 acting in cooperation with the rods 16 permits the cover to again assume its closed position.

When the receptacle 1 is in its horizontal loading position, and at which time its bottom rests on the ground, leaves and trash may then be readily swept into such receptacle much in the manner of a dustpan. At such time the receptacle 1 may be maintained stationary by hand engagement of the grip 11 of handle 9, or on the handle 24; the latter handle also being useful to dump the debris from the receptacle 1 when desired and which is accomplished with the cover 7 open, as in Fig. 4.

From the foregoing description, it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. A manually portable leaf and trash gatherer comprising a receptacle normally disposed in a vertical carrying position, the receptacle including a bottom, front, back, and sides; a fork-legged handle upstanding from the receptacle, the fork legs straddling the receptacle, means transversely pivoting the fork legs at their lower ends to adjacent sides intermediate the front and back of said receptacle whereby with the handle remaining upstanding the receptacle is swingable forwardly and downwardly from said vertical carrying position to a horizontal loading position, the handle including a post from which the fork legs extend above a lower end portion of said post, said lower end portion of the post being adjacent the back of the receptacle when the latter is in said horizontal loading position, and means between said lower end portion of the post and the back of the receptacle operative when the same are in said adjacent relation to automatically but releasably lock the receptacle in said horizontal loading position; said releasable locking means including a member vertically slidably mounted on said lower end portion of the post, the lower end of said member being formed as a catch element, and a bar fixed on the back of the receptacle formed with a notch into which said element is adapted to snap-engage; said bar being included in another handle on the receptacle at the rear thereof.
2. A device, as in claim 1, in which said member is a weight; there being control means which limit the downward movement of the weight.
3. A manually portable leaf and trash gatherer comprising a receptacle normally disposed in a vertical carrying position, the receptacle including a bottom, front, back, and sides; a fork-legged handle upstanding from the receptacle, the fork legs straddling the receptacle, means transversely pivoting the fork legs at their lower ends to adjacent sides intermediate the front and back of said receptacle whereby with the handle remaining upstanding the receptacle is swingable forwardly and downwardly from said vertical carrying position to a horizontal loading position, the handle including a post from which the fork legs extend above a lower end portion of said post, said lower end portion of the post being adjacent the back of the receptacle when the latter is in said horizontal loading position, and means between said lower end portion of the post and the back of the receptacle operative when the same are in said adjacent relation to automatically but releasably lock the receptacle in said horizontal loading position; said releasable locking means including a member vertically slidably mounted on said lower end portion of the post, the lower end of said member being formed as a catch element, and a bar fixed on the back of the receptacle formed with a notch into which said element is adapted to snap-engage; said bar projecting rearwardly from the back of the receptacle at right angles to the post; the lower end portion of the post being formed with a rearwardly opening locating cradle in which said bar seats when said catch is engaged in the notch.
